UNITED STATES PATENT OFFICE.

SYLVAIN VINCART-MOUZIN, OF NIMY, BELGIUM.

TUNNEL-KILN FOR BAKING POTTERY.

969,125.

Specification of Letters Patent. Patented Aug. 30, 1910.

Application filed February 10, 1908. Serial No. 415,160.

To all whom it may concern:

Be it known that I, SYLVAIN VINCART-MOUZIN, a subject of the King of Belgium, residing at Nimy, Belgium, have invented a certain new and useful Tunnel-Kiln for Baking Pottery, of which the following is a specification.

The present invention relates to a kiln in which pottery and porcelain-ware and the like, which must not be exposed directly to the fire gases, can be baked in continuous working.

In the arrangement, according to the present invention, the employment of special capsules for protecting the wares to be baked against the action of the fire gases is avoided. This has been accomplished essentially by providing double walls for the kiln-chamber proper, namely by building into the oven, beneath its ceiling, an intermediate ceiling and also at each of the sides an intermediate wall extending up to the intermediate ceiling, so that only the hollow space which surrounds the kiln-chamber proper at the sides and top is traversed by the heating gases. In the kiln tunnel, cars, movably mounted on balls, are provided to serve for the reception of the wares to be baked.

The outer walls of the kiln are of considerable thickness so as to present a considerable resistance to the outward passage of the heat. These walls consist of fireproof blocks capable of withstanding a temperature of 2000° Celsius, while the intermediate walls and the intermediate ceiling consist of thin slabs joined together in such a manner that the slabs may easily be exchanged during the working and offer a very small resistance to the passage of the heat to the interior chamber of the kiln. The substructure which serves for the support of the intermediate wall is not subjected to the direct influence of the fire gases.

A tight and yet expansible union between the slabs forming the intermediate partition, and the brick-work supporting the slabs is obtained by the provision of grooves filled with sand into which project the suitably shaped edges of the slabs. This arrangement makes it possible for the slabs, subjected to the highest heat, to expand freely so that their life is prolonged considerably. The wall of brick-work which supports the slabs is provided with the same grooves for the full length of the inter-

mediate lining so as to make the sand seal continuous by the use of the said grooves.

The exchange of the slabs forming the intermediate wall is effected through openings, cut into the exterior brickwork of the kiln, which as a rule are filled in or covered over by means of suitably shaped blocks or slabs.

The cars serving for the reception of the wares to be baked are movably mounted within the tunnel-kiln in such manner that the wares come as near as possible to the intermediate wall of the heating chamber, as the intensity of the radiating heat, as is well known, is inversely proportional to the squares of the distances.

In the accompanying drawings Figure 1 is a vertical longitudinal section of the complete kiln plant. Fig. 2 is a vertical cross-section on the line V W of Fig. 1, and line II-II of Fig. 5, through the central oven showing the entrance of the gas. Fig. 3 is a sectional plan through the air chambers (10). Fig. 4 is a section of the ovens in perspective. Fig. 5 is a sectional plan through the combustion chambers, and showing to the right and to the left the two parallel rows of cars. Fig. 6 is a vertical section on the line VI-VI of Fig. 5.

The exchangeable slabs of which the intermediate ceiling is composed are indicated by 1, and they are arranged with their edges in the channels 13 full of sand, supported by the columns 2. The columns 2 are placed between the two rows of cars (Fig. 2). The channels 13 may also be supported by short columns or supports disposed upon the thick lower walls of the kiln. The slabs of the intermediate wall are arranged with their lower edges resting in sand channels upon the thick lower walls of the kiln and are suitably arranged to fit with each other and with the slabs of the intermediate wall in the manner of tiles. Running upon balls 3 the cars 5 are provided according to a known arrangement to pass in opposite directions in two rows in the same tunnel. These two rows of cars moving in opposite directions provide a perfect exchange of heat between the objects destined to be baked and those which have undergone the baking.

The gases leave the generator and enter the central portion or chamber of the kiln by the conduit 8. They reach at the point indicated 11, four entrance orifices for

warm air and combustion takes place at this point. The flaming gases traverse the central part of the kiln and dividing into two parts, proceed, one part to the right end of the kiln, the other to the opposite end, passing through the conduits which are placed so as to present a tortuous passage. The products of combustion escape by the flues 4, and the heat passing through the walls of the flues 4 is absorbed by the air in the passages 10 advancing in the opposite direction. As shown in Fig. 3, the passages 10 are placed in a winding manner above the combustion chambers 9, and receive the heat which passes through the arches 6, the continual cooling effect due to the circulation of air in the passages 10, having the effect of prolonging the life of the arches. As shown in Figs. 2 and 5, all of the combustion chambers 9, are, for the reasons stated, lined or inclosed by the air passages 10.

Though the plates 1 of the intermediate ceiling or inner lining are subjected to a very high temperature their life is prolonged by reason of the fact that they are cooled on one side by radiation to the articles to be baked which pass through the kiln tunnel upon the cars.

Under the kiln at the center there is provided an open space 7 for the purpose of observation of the operations.

In the ordinary construction of a baking kiln with double walls, the combustion passages in which the flames circulate are formed by a series of parallel walls depending from the external arch or kiln ceiling. These walls are intended to support thin plates protecting the articles to be treated from the direct action of the flames continually circulating between these walls, they are between two fires, and soon perish, if the temperature rises very much. I therefore omit these walls, of which the destruction is inevitable, and replace them, by the supports 2 placed below the inner lining or ceiling 1 and in the same space as the article to be baked. The supports are thus screened from the flames and the kiln chambers in consequence are capable of resisting very high temperatures, which permit the thorough baking of the china. The external arch is constructed of silica (dinos-stella) or magnesia or bauxite, and because of the air circulation, it can resist a temperature of 2900 C. 12 are passages for cold air or water.

What I claim as my invention and desire to secure by Letters Patent is:—

1. A tunnel kiln for uninterrupted operation, comprising a kiln chamber having a continuous passage therethrough, slabs forming intermediate walls and ceiling, separating the kiln chamber into a heating compartment and combustion compartments, supports having sand-sealing channels to

receive the supporting edges of said slabs, and air passages extending over and contiguous to the combustion compartments for conveying heated air to support combustion in said combustion compartments.

70

2. A tunnel kiln especially for baking clay, porcelain and glazed wares in uninterrupted working, the combination of supporting walls of the kiln chamber, channels filled with sand mounted on the supporting walls, slabs, forming partitions, said slabs dipping with their edges into the channels and dividing the kiln chamber into two compartments, the upper one receiving the heating gases, while the lower one receives the goods upon carriers, capable of running through the lower compartment of the kiln chamber, and balls upon which said carriers are mounted, substantially as described.

75

3. A tunnel kiln especially for baking clay, porcelain and glazed wares in uninterrupted working, the combination of supporting walls of the kiln chamber, channels filled with sand and mounted on the supporting walls, slabs, forming partitions, said slabs dipping with their edges into the channels and dividing the kiln chamber into two compartments, the upper one receiving the heating gases, while the lower one receives the goods upon carriers, capable of running through the lower compartment of the kiln chamber, and balls upon which said carriers are mounted, substantially as described.

80

4. A tunnel kiln especially for baking clay, porcelain and glazed wares in uninterrupted working, the combination of supporting walls of the kiln chamber channels filled with sand mounted on the supporting walls, slabs, forming partitions, said slabs dipping with their edges into the channels and dividing the kiln chamber into two compartments, the upper one receiving the heating gases, while the lower one receives the goods upon carriers, capable of running through the lower compartment of the kiln chamber, balls upon which said carriers are mounted, and an inspecting chamber beneath the lower compartment of the kiln chamber, substantially as described.

95

5. In a tunnel kiln especially for baking clay, porcelain and glazed wares in uninterrupted working, the combination of supporting walls of the kiln chamber, channels filled with sand mounted on the supporting walls, slabs, forming partitions, said slabs dipping with their edges into the channels and dividing the kiln chamber into two compartments, the upper one receiving the heating gases, while the lower one receives the goods upon carriers, capable of running through the lower compartment of the kiln chamber, substantially as described.

100

6. A tunnel kiln for uninterrupted operation, comprising a kiln chamber having a

continuous passage therethrough, parallel tracks extending through said passage, carriers for the wares to be subjected to heat, adapted to travel in opposite directions upon 5 said tracks, whereby an interchange of heat is effected between the outgoing and incoming wares, and removable slabs and intermediate walls supported upon columns within the kiln chamber and separating said 10 chamber into a lower heating compartment and upper combustion compartments.

7. A tunnel kiln for uninterrupted operation, comprising a kiln chamber having a continuous passage therethrough, parallel 15 tracks extending through said passage, carriers for the wares to be subjected to heat, adapted to travel in opposite directions upon said tracks, whereby an interchange of heat is effected between the outgoing and 20 incoming wares, removable slabs and intermediate walls supported upon columns within the kiln chamber and separating said chamber into a lower heating compartment and upper combustion compartments and 25 air passages situated above said combustion

compartments and connected at their ends alternately to cause the air to follow a tortuous path, and means for conveying the heated air to the combustion compartments.

8. A tunnel kiln for uninterrupted operation, comprising supporting walls for the kiln chamber, a continuous passage through the chamber, slabs having depending edges or flanges and forming an intermediate ceiling to divide the chamber into a heating 30 compartment and combustion compartments, air passages situated above and extending over the combustion compartments for conveying heated air to support combustion, and air-ducts leading to said air passages, 35 said air-ducts and said flues being contiguous in the kiln walls to permit of an interchange of heat.

In testimony whereof I have hereunto signed my name to this specification in the 45 presence of two subscribing witnesses.
